(57) **CLAIM**

The ornamental design for a squeegee with suction cup, as
shown and described.

DESCRIPTION

FIG. 1 is a perspective view of the squeegee with suction cup
according to the invention;

FIG. 2 is a top view of the squeegee with suction cup as
shown in FIG. 1;

FIG. 3 is a front view of the squeegee with suction cup as
shown in FIG. 1;

FIG. 4 is a right side view of the squeegee with suction cup
as shown in FIG. 1;

FIG. 5 is a rear view of the squeegee with suction cup as
shown in FIG. 1;

FIG. 6 is a left side view of the squeegee with suction cup
as shown in FIG. 1; and,

FIG. 7 is a bottom view of the squeegee with suction cup as
shown in FIG. 1.

The broken lines showing a suction cup and hook in FIGS.
1 and 3-6 are for illustrative purposes only and forms no part
of the claimed design.
